(57) CLAIM

The ornamental design for a portable media player, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyright rights whatsoever. FIG. 1 is a top front perspective view of a portable media player according to an embodiment of my new design; FIG. 2 is a front view thereof; FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines and shading lines throughout the figures are for illustrative purposes or to show contour only and form no part of the claimed design.
